UNITED STATES PATENT OFFICE

GEORGE L. TICEHURST, OF BAKERSFIELD, CALIFORNIA

FIRE BRICK

Application filed September 14, 1928. Serial No. 306,026.

The present invention relates to improvements in bricks and has reference more particularly to a fire brick for boilers, using oil and gas burners.

5 One of the important objects of the present invention is to provide a fire brick of the above mentioned character wherein the same comprises a body portion having superimposed thereon particular shaped projections

10 for affording means to separate the gas that usually escapes upwardly through the flue and stack, the projections acting as a fuel saver and further permitting a hotter fire to be obtained.

15 Still a further object of the invention is to provide a fire brick of the above mentioned character that can be constructed at a very low cost, the same being at all times positive and efficient in carrying out the purpose for which it is designed, the bricks being further simple in construction and strong and durable.

20 Other objects of the invention will become apparent as the nature of the invention 25 proceeds and when taken in connection with the accompanying drawings.

In the accompanying drawings, forming a part of this application and wherein like reference characters designate like parts 30 throughout the several views:

Figure 1 is a side elevation of my improved fire brick.

Figure 2 is a top plan view thereof, and

35 Figure 3 is an end elevation of the fire brick.

Figure 4 is an elevational view of a furnace lining wall provided with the bricks constructed in accordance with the present invention.

40 In the drawings, wherein for the purpose of illustration is shown the preferred embodiment of my invention, the numeral 1 designates generally my improved fire brick, the same comprising a substantially rectangular shaped body 2, on the top face of which is

45 formed a series of projections denoted by the reference character 3. Each projection is of triangular shape in side elevation and as is shown more clearly in Figures 2 and 3, a front and rear face 4 and 5 of each projection

gradually converge toward the upper edge 6.

A fire brick of this character is particularly adapted to be used in boilers that employ oil or gas burners, the bricks, of course, being suitably arranged within the boiler, about the 55 inner periphery thereof, in a manner to constitute a lining for the boiler, and with the projections extending in the path of flow of the gases that escape upwardly through the flue and stack.

60 In Figure 4 I have shown a furnace lining wall constructed from the bricks embodied in the features of construction above noted and from a study of said figure it will be seen that the bricks provide a lining for the side and top 65 walls of the boiler or furnace with the teeth or projections extending inwardly with respect to the furnace so as to be in the path of the flow of gases and serve to break up the molecules of gas and carbon, so that the possibility of the carbon caking on the interior 70 of the flues is almost negligible.

75 I have found in firing large boilers that the oil or gas burners consume considerable fuel, and furthermore, burnt out fire bricks must be replaced very frequently at a very large expense.

80 Also, where a poor grade of oil is used, the necessary amount of steam desired cannot be obtained. These objections are all overcome by the use of my improved fire brick as has been efficiently demonstrated.

85 The formation of the teeth like projections on the upper face of each brick will prevent the accumulation of carbon and will further act as a means for breaking up the particles of fuel to aid in the proper burning of the fuel.

90 While I have shown the preferred embodiment of my invention, it is to be understood that various changes in the size, shape, and arrangement of parts may be resorted to, without departing from the spirit of the invention or the scope of the appended claim.

95 Having thus described my invention, what I claim as new is:

100 In a fire brick of the class described, a substantially elongated rectangular body, teeth-like projections formed on the upper face thereof inwardly from the opposite longitudi-

dinal edges of the body, said projections being of triangular shape in side elevation, the opposite side faces of each projection tapering gradually towards the apex, said projections being arranged on said body in longitudinal alinement, the endmost of said projections being disposed inwardly from the adjacent end edges of said body.

5 In testimony whereof I affix my signature.

10

GEORGE L. TICEHURST.
